UNITED STATES PATENT OFFICE.

RUSSEL H. BREMER, OF NEW YORK, N. Y.

REFRIGERATOR.

1,357,839.

Specification of Letters Patent. Patented Nov. 2, 1920.

Application filed September 6, 1919. Serial No. 322,030.

To all whom it may concern:

Be it known that I, RUSSEL H. BREMER, a citizen of the United States, residing at New York city and State of New York, have 5 invented new and useful Improvements in Refrigerators, of which the following is a specification.

This invention relates to refrigerators and has for its object the provision of a refrigerator in which the refrigerating action is accomplished by evaporation of water disposed within the device, the device being 10 molded from extremely porous material whereby to facilitate evaporation.

15 An important object is the provision of a device of this character which is provided at its upper portion with oppositely disposed controllable ventilators whereby the evaporating action may be hastened.

20 Another and more specific object is the provision of a refrigerator of this character which is provided in its lower portion with a water containing pan into which extend wicks disposed within grooves in the 25 walls of the device.

An additional object is the provision of a 30 device of this character which will be simple and inexpensive in manufacture, highly efficient and inexpensive in use as eliminating the necessity for ice, durable and sanitary in service, and a general improvement in the art.

With the above and other objects and advantages in view, the invention consists in 35 the details of construction to be hereinafter more fully described and claimed and illustrated in the accompanying drawing in which—

Figure 1 is a front elevation of my refrigerator,

40 Fig. 2 is a side elevation,

Fig. 3 is a cross sectional view on the line 3—3 of Fig. 1, and

45 Fig. 4 is a vertical sectional view on the line 4—4 of Fig. 2.

Referring more particularly to the drawings, the numeral 10 designates the body of the refrigerator which is molded from extremely porous material such as plaster of 50 Paris cement or various clay substances noted for their extreme porosity. This body is formed with its front open, as shown, and all the other faces closed except the sides 11 which are provided with cylindrical holes 55 12 within which are secured ventilators in-

dicated broadly by the numeral 13. These ventilators will be hereinafter described more in detail.

Hinged upon the front of the body, as shown at 14, is a door 15 which is preferably 60 hollow and filled with any suitable well known heat insulating material indicated at 16. This door is so constructed as to have flanges 17 overhanging the edges of the open front. A suitable catch mechanism 18 is 65 provided for holding the door normally closed.

Formed upon the inner faces of the sides and back walls of the body 10 are vertically extending grooves 19 which extend to points 70 substantially on a line with the bottoms of the ventilator holes 12. The inner portions of these grooves 19 are formed wider than their entrances and are adapted to have disposed therein wicks 20 which will be consequently retained in position. Disposed within the bottom portion of the body 10 is a pan 21 containing water to which is preferably added a small amount of ammonium chlorid. This pan is provided adjacent the upper edges of its side and back walls with recesses 22 which register with the lower ends of the grooves 19 and through which the wicks 20 extend into the water contained within the pan. A cover 85 plate 23 is seated upon the pan 21 and is preferably flush with the lower edge of the door opening and this cover forms a closure for the pan. This cover plate is provided preferably adjacent its corners, with holes 90 24 through which the operator may insert his fingers for lifting it out when it is desired to replenish the water within the pan.

Each ventilator member 13 comprises a cylindrical casing 25 secured within the 95 opening 12 and having a flange 26 bearing against the wall. The outer end of each cylindrical casing 25 is closed except for a plurality of perforations 27. Rotatably mounted upon the closed end of the casing 100 30 is a plate 28 carrying an operating handle 29 and provided with a segmental opening 30 adapted to uncover a desired number of said perforations 27.

In the use of the device it will be seen that 105 water disposed within the pan 21 will be drawn through the wicks 20 through natural capillary action and will be thus supplied to the porous body. Evaporation will of course occur which will result in drawing 110

the heat from the interior of the body, thus providing an efficient refrigerating action. By regulating the plates 28 so as to uncover more or fewer of the perforation 27, the action of the ventilators 13 may be controlled.

From the foregoing description and a study of the drawing it will be apparent that I have thus provided a simply constructed refrigerator which will be highly efficient in cooling action without the employment of ice, the device being consequently very economical in use.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A refrigerator formed as an integral hollow body of porous material, having a door opening and a door therefor, ventilating means within the upper portion of the body, a pan located within the bottom portion of the body and containing water, a cover for said pan forming the bottom of the refrigerating space, the cover being provided at its edges with notches and the inner surfaces of the walls of the body being formed with vertical grooves registering with said notches and having overhanging side edges, and wicks disposed within said grooves, passing through said notches, and dipping into the pan.

In testimony whereof I affix my signature.

RUSSEL H. BREMER.
